United States Patent

Des. 236,635
Patented Sept. 2, 1975

236,635

RECEPTACLE FOR BANK DEPOSITS

Aaron I. Friedman, 425 2nd St.,
San Francisco, Calif. 94107

Filed Feb. 28, 1974, Ser. No. 447,041

Term of patent 14 years

Int. Cl. D6—04

U.S. Cl. D31—22

FIG. 1

FIG. 2

FIG. 3

FIG. 4

FIG. 5

FIG. 1 is a perspective view of a receptacle for bank deposits showing my new design;

FIG. 2 is a front elevational view on a reduced scale;

FIG. 3 is a side elevational view on a reduced scale;

FIG. 4 is a bottom plan view on a reduced scale; and

FIG. 5 is a top plan view on a reduced scale.

The rear elevational view is the same as the front elevational view, and both side elevational views are the same.

I claim:

The ornamental design for a receptacle for bank deposits, substantially as shown and described.
